UNITED STATES PATENT OFFICE.

ABRAHAM L. ELIASOFF AND CHARLES BIRNBAUM, OF NEW YORK, N. Y.

JEWELRY-CLASP.

1,352,591.

Specification of Letters Patent. Patented Sept. 14, 1920.

Application filed March 8, 1920. Serial No. 364,084.

To all whom it may concern:

Be it known that we, ABRAHAM L. ELIASOFF and CHARLES BIRNBAUM, citizens of the United States, and residents of the city of New York, borough of Manhattan, in the county and State of New York, have invented certain new and useful Improvements in Jewelry-Clasps, of which the following is a full, clear, and exact description.

Among the principal objects which the present invention has in view are: To avoid the accidental separation of the separable parts of a clasp such as disclosed, and the consequent loss of the article with which it is associated; to produce a neat and finished appearance in the article, and to simplify and strengthen the construction of the parts of the clasp.

Drawings.

Figure 1 is a top plan view on enlarged scale of a clasp constructed and arranged in accordance with the present invention;

Fig. 2 is a sectional view, the section being taken as on the line 2—2 in Fig. 3;

Fig. 3 is an edge view of the article as shown in Fig. 1;

Fig. 4 is a plan view of the clasp shown in its open condition; and

Fig. 5 is a cross section, the section being taken as on the line 5—5 in Fig. 1.

Description.

The herein disclosed clasp is usually employed for fastening necklaces. Heretofore such clasps have consisted of a barrel type wherein a spring latch has been inserted, the parts whereof open to engage the barrel member. A second type has embodied the more graceful flat or box body. An insert correspondingly flat has been used, the sides whereof spring apart to engage some member in the box body. In some cases a bridge has been extended from the box body to catch a hook-like insert member, after the same has been drawn from the box body. These forms of clasp have proved objectionable for the reason that in the first mentioned instance, when, as accidentally has occurred, the insert member becomes detached, the separating portions of the latch, and parts associated therewith, have opened, with the result that the necklace has fallen and often been lost. The objection to the last mentioned construction has been that it is clumsy and has marred the appearance

of what otherwise is an article of ornamental wear.

As seen in the drawings, the clasp is of the flat, box-like form, and has an ornamental top 10. The top 10 is removed from the bottom 11 very slightly, to form a narrow space 12 therebetween. The top 10 and bottom 11, are structurally united by small posts 13, 14, 15 or 16, the outer surfaces 65 whereof are flush with the edges of the top and bottom portions.

The snap 17 is intended for insertion between the posts 15, with which in service the separable ends of the snap engage. The snap 70 is elongated, and is constructed from resilient material, cut to U-shape, to form the channel 18, and an enlarged opening 19, that produces the yielding or resilient section 20.

At the opposite or outer end of the snap 75 17, the link 21 is fastened to one of the sides of the snap, and preferably to that having the shoulders 22. The ring 21 simulates in appearance a ring 23, at the opposite end of the clasp, and set up from the 80 bottom 11.

Through the rings 21 and 23 are passed the eyelets 24 and 25 at the ends of the string 26, on which beads or other ornaments are usually threaded. Adjacent the 85 extremity of the opposite side of the snap 17 to that having the shoulders 22, is a nick 27, adapted to engage one of the posts 15 when the snap has been fully inserted between the top and bottom of the clasp. In 90 order to insert the snap 17 in the latch, the said snap must first be adjusted with reference to the post 16, so that the sides of the snap pass around the said post. This is accomplished by disposing the snap in a position substantially transverse the length of the clasp. This operation is assisted by the curved edge 28 of the end of the snap having the nick 27. The snap is then drawn until the post 16 is in the enlarged portion 19 100 of the snap, when it may be swung around on the post 16 to press the snap lengthwise of the clasp. From this position, as shown in Fig. 4, it may be moved to the position shown in Fig. 1, where the shoulders 22 engage the post 15 on one side of the clasp, while the nick 27 engages the post 15 on the opposite side.

If now by accident the snap 17 becomes 110 disengaged from the post 15, and the strain on the string 26 be sufficient to draw the snap out of the latch, it would only result

in the snap catching on the post 16 in the position shown in Fig. 4. To become totally disengaged or separated from the body of the clasp, it would be necessary to tighten 5 the string 26 sufficiently to permit the snap 17 swinging to the position perpendicular to the lengthwise axis of the body of the clasp which would shorten the circlet of the string 26 more than in its regular service 10 position, a condition improbable if not impossible.

As seen best in Fig. 2 of the drawings, when the snap is inserted in service position within the body of the clasp, the inner end 15 thereof rests between the posts 14 which serve to steady the snap 17 and to hold same in service.

Claims.

- 20 1. An article as characterized comprising a thin box-like body portion having parallel closely spaced top and bottom portions structurally connected by edge flush posts, two of said posts being oppositely disposed 25 in paired relation; an elongated resilient hook-like snap, adapted for extension between said paired posts, the free ends of said snap being provided adjacent the extremities thereof with shoulders for engaging 30 said posts; and a third post intermediate said paired posts in spaced relation thereto, said

thereto, said third post being disposed between the sides of said hook-like snap to guide the same when moved in and out between said top and bottom and for engaging 35 said snap at the bend of the hook thereof when drawn from between said first mentioned posts.

2. An article as characterized, comprising a thin box-like body portion having parallel 40 closely spaced top and bottom portions structurally connected by edge flush posts, two of said posts being oppositely disposed in paired relation; an elongated resilient hook-like snap, adapted for extension between 45 said paired posts, the free ends of said snap being provided adjacent the extremities thereof with shoulders for engaging said posts; a third post intermediate said paired posts in spaced relation thereto, said 50 third post being disposed between the sides of said hook-like snap to guide the same when moved in and out between said top and bottom and for engaging said snap at the bend of the hook thereof when drawn from 55 between said first mentioned posts; and a ring mounted on said snap extended from one side thereof in line with the opening between the hook-like sides of said snap for equalizing the strain on said snap.
